UNITED STATES PATENT OFFICE.

JEAN CORNE, PIERRE DUFFAU, AND PIERRE BARATHIÉ, OF VILLENEUVE-SUR-LOT, FRANCE.

CARBURETER FOR EXPLOSION-MOTORS.

SPECIFICATION forming part of Letters Patent No. 731,547, dated June 23, 1903.

Application filed March 3, 1903. Serial No. 145,982. (No model.)

To all whom it may concern:

Be it known that we, JEAN CORNE, PIERRE DUFFAU, and PIERRE BARATHIÉ, citizens of the Republic of France, and residents of Vil-
leneuve-sur-Lot, Lot-et-Garonne, in the Republic of France, have invented certain new and useful Improvements in Carbureters for Explosion-Motors, of which the following is a specification.

This invention relates to a carbureter for explosion-motors in which the carbureting operation is rendered uniform by regulating the quantity of spirit introduced while the motor is working and is intended to provide means for insuring such regulation.

In the accompanying drawings one form of a carbureter constructed in accordance with this invention is illustrated.

Figure 1 is a vertical section; Fig. 2, a plan; Fig. 3, a side elevation, and Fig. 4 a horizontal section along the line 3 4 in Fig. 1.

The apparatus comprises a mixing or carbureting chamber *a*, a distribution-chamber *b*, which can be raised or lowered at any moment, as subsequently described, a distribution-valve *c* for the spirit, a lever *d* for opening the valve *c*, a cam *f*, operated by the motor and acting on the lever *d*, a register *g* for regulating the admission of air, and a screw-cap and wheel *v*, regulating the position of the distribution-chamber.

The bottom of the mixing-chamber *a* communicates, through a tubular connection *j*, with the motor suction apparatus. Above the mixing-chamber *a* is a vertical tubular extension *k*, which has an external screw-thread and is slotted on one side through its whole length. Around this tubular extension holes *o* are formed in the top of the chamber *a* for the admission of air. Over these holes the register *g* is arranged, and consists of a perforated disk, which can be turned so as to close the air-holes *o* to a certain extent and is fixed in position by a screw *m*, which engages in a slot *n*, formed in the register. Finally the chamber *a* is cast in one piece with a vertical plate or bracket *z*, which serves for fixing the carbureter onto a support of any kind, and it is provided with lugs *p* for the pivotal connection of the operating-lever *d*, one arm

of which enters the said chamber, the other arm projecting therefrom.

The distribution-chamber is formed by a cylinder *b* cast in one piece with a tubular part *r* for admitting the spirit and is closed at the top by a plug *s*.

The valve *c* is located in the chamber *b* and held against its seat by a spiral spring *l*.

The chamber *b* is arranged in the tubular extension *k* of the mixing-chamber, its tubular attachment *r* being placed in the vertical groove of the said extension *k*.

A powerful spiral spring *q* is coiled around the chamber *b* and bearing at opposite ends on an internal shoulder of the extension, and an external shoulder *x* on the chamber *b* constantly tends to keep the chamber *b* raised. Finally a perforated wheel *v* is formed integral with an internally-screw-threaded cap, which surrounds the distribution-chamber *b* and screws onto the tubular extension *k*.

The cap bears upon the shoulder *x* of the distribution-chamber *b*, and in proportion as the wheel is turned to screw down the cap the chamber *b* is lowered and compresses the spring *q*. If the wheel be turned to unscrew the cap, the spring raises the chamber *b*. In these movements the tubular feed-piece *r* in the distribution-chamber is displaced in the vertical slot formed in the tubular part *k*.

The wheel is retained in its different positions by means of a pin, which engages in a stationary hole and in one of the holes *y*, formed in the circumference of the said wheel. The unscrewing of the wheel under the action of vibration is thus prevented, as is consequently any irregularity.

The action of the carbureter is as follows: The tubular feed-piece *r* of the distribution-chamber being connected to a spirit-reservoir with a constant level at each suction-stroke of the motor the cam *f* acts on the valve-lever *d* and forces it to turn on its pivot. In this movement the inner arm of the lever raises the valve *c* and a certain quantity of spirit enters the mixing-chamber in the form of spray. At the same time the suction action of the motor causes the admission into this same chamber through the holes *o* of a quantity of air regulated once for all by

means of the register. The mixture is rendered complete and is conveyed to the motor.

In order to regulate the carbureting operation while the motor is acting according to the speed of the latter and the various circumstances, all that is necessary is to raise or lower the valve *c* and valve-chamber to a certain extent, so as to change the stroke of this valve, and consequently to enable a smaller or greater quantity of spirit to enter the mixing-chamber. This is very easily effected by turning the wheel *v*, whereby the chamber *b* is lowered, and consequently the tailpiece of the valve *c*. It will be understood that as the cam *f* raises the inner arm of the lever *d* to the same height again each time this arm, which acts on the tailpiece of the valve, will raise the latter all the farther as its action begins at a lower point—that is to say, as the distribution-chamber *b* has been lowered by the action of the wheel *v*. This carbureter, moreover, enables the spirit to be introduced at any moment of the stroke, particularly slightly before the opening of the motor admission-valve. For this purpose it is only necessary that the cam *f*, which acts on the lever *d*, should be suitably mounted.

Having now described our invention, what we claim as new, and desire to secure by Letters Patent, is—

1. A carbureter for explosion-motors comprising a mixing or carbureting chamber *a*, holes *o* putting said chamber in communication with the outside, tubular parts *j* and *k* made integral with said chamber, a distribution-chamber *b* arranged in the tubular part *k* so as to be capable of moving lengthwise, a coil-spring *q* arranged between an internal shoulder of the tubular part *k* and an external shoulder of the distribution-chamber *b*, a wheel-nut *v* adapted to be screwed more or less on the tubular part *k* and which bears at the top against the shoulder *x* of the distribution-chamber, a valve *c* arranged in the distribution-chamber *b* and stopping the connection between said chamber and the mixing-chamber *a*, a coil-spring *l* which causes constantly the valve *c* to bear against its seat, a lever *d* pivoted on the wall of the chamber *a* and provided with an arm extending below the tailpiece of valve *c* and an external arm, and finally a cam *f* operated by the motor and acting on the lever *d* to raise the valve *c* from its seat, substantially as and for the purpose set forth.

a lever *d* pivoted on the wall of the chamber *a* and provided with an arm extending below the tailpiece of the valve *c* and an external arm, and finally a cam *f* operated by the motor and acting on the lever *d* to raise the valve *c* from its seat, substantially as and for the purpose set forth.

2. A carbureter for explosion-motors comprising a mixing or carbureting chamber *a*, holes *o* putting said chamber in communication with the outside, a register *g* movable on the holes *o*, a screw *m* to fix in position said register, a tubular part *j* connecting the chamber *a* with the motor, a tubular part *k* made integral with the chamber *a*, provided with an external thread and slotted on one side through its whole length, a distribution-chamber *b* arranged in the tubular part *k* so as to be capable of moving lengthwise, a tubular part *r* made integral with the chamber *b* and arranged in the vertical tubular part *k*, a coil-spring *q* arranged between an internal shoulder of the tubular part *k* and an external shoulder of the distribution-chamber *b*, a wheel-nut *v* adapted to be screwed more or less on the tubular part *k* and which bears at the top against the shoulder *x* of the distribution-chamber, a valve *c* arranged in the distribution-chamber *b* and stopping the connection between said chamber and the mixing-chamber *a*, a coil-spring *l* which causes constantly the valve *c* to bear against its seat, a lever *d* pivoted on the wall of the chamber *a* and provided with an arm extending below the tailpiece of valve *c* and an external arm, and finally a cam *f* operated by the motor and acting on the lever *d* to raise the valve *c* from its seat, substantially as and for the purpose set forth.

In witness whereof we have hereunto set our hands in the presence of two witnesses.
